(57) CLAIM

The ornamental design for a urinal holder, as shown and described.

DESCRIPTION

FIG. 1 is a front perspective view of a urinal holder shown attached to a portion of a bedrail illustrated in dotted line; FIG. 2 is a front view thereof; FIG. 3 is a left side view thereof; FIG. 4 is a rear view thereof; FIG. 5 is a top view thereof; and, FIG. 6 is a bottom view thereof.

The bedrail shown in dotted line illustrates the environment in which the urinal holder is used and forms no part of the design.
